UNITED STATES PATENT OFFICE

170,248

WHEEL ORNAMENT FOR MOTOR VEHICLES

Carl W. Sundberg, Birmingham, Mich., assignor
to Sundberg & Ferar, Royal Oak, Mich., a co-
partnership

Application January 7, 1953, Serial No. 23,048

Term of patent 3½ years

(Cl. D14—30)

To all whom it may concern:

Be it known that I, Carl W. Sundberg, a citizen of the United States of America, residing at 1260 Lyonhurst Avenue, in the city of Birmingham, State of Michigan, have invented a new, original, and ornamental Design for a Wheel Ornament for Motor Vehicles, of which the following is a specification, reference being had to the accompanying drawing, forming a part hereof.

Fig. 1 is a front elevation of a wheel ornament for motor vehicles, showing my new design.

Fig. 2 is a side elevation taken at the front end of the wheel ornament of Fig. 1.

Fig. 3 is a vertical sectional view on the line 3—3 of Fig. 1.

Fig. 4 is a vertical sectional view on the line 4—4 of Fig. 1.

I claim:

The ornamental design for a wheel ornament for motor vehicles, as shown.

CARL W. SUNDBERG.
